UNITED STATES PATENT OFFICE.

DAVID R. SAUNDERS, OF COLUMBUS, MISSISSIPPI.

CAR-HEATER.

1,039,819.

Specification of Letters Patent.

Patented Oct. 1, 1912.

Application filed September 25, 1911. Serial No. 651,213.

To all whom it may concern:

Be it known that I, DAVID R. SAUNDERS, a citizen of the United States, residing at Columbus, Lowndes county, Mississippi, have invented a certain new and useful Improvement in Car-Heaters, of which the following is a full, clear, and exact description, such as will enable others skilled in the art to which it appertains to make and use the same, reference being had to the accompanying drawings, forming part of this specification, in which—

Figure 1 is a vertical section taken through the center of a car body, which car is equipped with a heater of my improved construction. Fig. 2 is a vertical section taken through the center of my improved heater. Fig. 3 is a horizontal section taken on the line 3—3 of Fig. 2.

20 My invention relates to a heater particularly intended for use in connection with railroad cars utilized for the shipment of fruits, vegetables and like perishable products during the cold seasons of the year.

25 Ordinarily the refrigerator cars, which in the summer and warmer months are packed with ice and utilized for shipment of goods that are perishable, are during cold weather used for shipment of fruits, vegetables, and the like from points in a mild climate to points in colder climates, and during the use of these cars in the colder months it is necessary to heat the interior of the cars in order to protect and preserve the products 35 being transported.

The ordinary methods now practised for heating the interior of the cars is to run the cars onto a side track, at various stages during the shipping trip, and to place stoves and like heating devices within said cars, but such methods involve the expenditure of considerable time and labor on the part of railway employees, besides greatly delaying the shipping movements of the cars and their contents.

40 I propose to overcome the objectionable features heretofore existing in the heating of cars, during the shipment of perishable goods in cold weather, by equipping the cars with heating devices which can be operated continuously while the car is in transit, and which will maintain a uniform degree of heat within the car, thereby preventing the contents of the car from becoming frozen 45 during shipment.

My improved heating device is preferably located below the floor line of the car, and is arranged so that when in operation, a circulation of warm air is established, thus maintaining practically an even heat throughout the entire space within the car.

To the above purposes my invention consists in certain novel features of construction and arrangement of parts hereinafter more fully described, and claimed.

Referring by numerals to the accompanying drawings, 1 designates the body of a car which is of the type usually employed for shipping fruit, vegetables and like perishable goods, during the warmer months of the year, and my improved heating device is applied to the floor of a car, preferably at the point beneath one of the ice racks, and immediately adjacent one of the end walls of said car.

Formed in the floor of the car is an opening 2, and seated therein is the open upper end of the outer shell or casing 3 of the heater. The lower end of this shell or casing is closed and located within the lower portion of said shell and fixed to the bottom thereof is a fire pot 4, one side of which is provided with a laterally projecting box-like housing 5 which extends to and communicates with an opening 6 formed in the lower portion of a wall of said shell, and which opening is normally closed by a hinged door 7.

Formed in the bottom plate of the shell 3 are a series of perforations 8 for the purpose of admitting air to the fire pot, and arranged to slide on the underside of this bottom plate is a perforated draft plate 9. This draft plate 9 can be adjusted so that its perforations coincide with the perforations in the bottom plate, thus permitting air to enter the fire pot, and when desired, the plate can be shifted so as to cut off this draft.

Located within the fire pot 4, a short distance above the bottom plate is a perforated plate 10, adapted to support a removable grate 11, in which the fire of my improved heater is formed.

12 designates an inner wall of the casing which is supported in any suitable manner within the shell or casing 3, and said inner wall is smaller in diameter than the outer casing, thereby forming an annular space 13, between said inner wall and the wall of the outer casing. The wall 12 terminates a short

distance above the bottom plate of the outer casing in order to permit the air which is drawn downwardly through the annular space 13 to discharge into and pass upward through the space within said inner wall shell.

Formed in the top of the firepot 4 is an opening 14 and arranged to slide on top of said fire pot, to the sides of this opening, are plates 15 utilized for the purpose of controlling the discharge of fuel through said opening 14 into the grate 11.

16 designates a fuel chute of tubular form, the lower portion of which is centrally arranged within the wall 12, and the lower end of this chute terminates immediately above the opening 14. The upper portion of this chute extends upwardly along the side or end wall of the car a sufficient distance to form an ample fuel magazine, and the upper end of said chute is provided with a hinged door 18. A screen or grate 19 is positioned on the car floor immediately over the casing 3 and wall 12 and the upper portion of the fuel chute extends through the center of this screen or grating.

When my improved heater is equipped for service, chute 16 is filled with fuel preferably charcoal, and after a quantity of charcoal has been ignited within the grate 11 and is in an incandescent state, said grate is inserted through the opening 6 and is positioned on the perforated plate 10 within the fire pot. The slides 15 are now adjusted to regulate the discharge of charcoal from the lower end of the tube 16, and as the charcoal burns away within the grate 11 fresh charcoal from the chute 16 will discharge into said grate 11 to supply the fire therein. The ashes resulting from the burning charcoal within the grate 11 will naturally gravitate through the openings in said grate, and will pass from thence downward through the perforations in the plate 10, into the space between said plate and the bottom plate of the casing 3, and when desired, these ashes may be removed by opening the door 7 and passing a suitable tool over the bottom plate of the casing.

50 The air necessary to support the combustion of the charcoal within the grate 11 is admitted to the perforated draft plate 9 and perforations in the bottom plate of the casing 3. Where charcoal is used as a fuel, the products of combustion resulting from the burning of the charcoal are comparatively small and said products of combustion escape through the apertures in the bottom of the casing 3 and a certain proportion of said products of combustion will rise through the tube 16 and escape through the crack beneath the door 18 which closes the upper end of said tube. After a fire has been started in the grate, the air around the fire pot 4 naturally becomes heated, and in such con-

dition rises through the space within the wall 12 and passes from thence upwardly into the space within the car. As this action continues, the cold air within the car will naturally be forced to the bottom of the space within said car, and said cold air will be drawn downward through the annular space 13 between the wall 12 and wall of the casing 3, owing to the partial vacuum established within the lower end of the wall 3, by 70 the heat generated within the fire pot and which heat causes the air surrounding the fire pot to rise, and the cold air discharging beneath the lower end of the wall 12 strikes the fire pot, and is in turn heated and rises, 75 thereby forming a continuous current which is maintained as long as the fire is maintained within the fire pot. The cold air is drawn from its natural place at the bottom of the space within the car body, and the 80 heated air rising in the column develops no opposition to the free circulation of the air through the car and therefore the heated air will, within a very short time, be evenly distributed throughout the entire space in 85 the car.

A heating device of my improved construction is comparatively simple, can be operated at very little cost and provides a simple means for effectually heating the entire 95 space within a car, which is being utilized for carrying goods which are liable to become frozen when shipped in cold weather.

Ordinarily the walls of refrigerator cars are insulated against the radiation of heat 100 and cold, in order to maintain a comparatively even degree of temperature within said car, and for this reason my improved heater is of particular advantage when combined with an ordinary refrigerator car during the warmer months and can remain in service during the colder months by the installation of one of the heaters and thus the car so equipped can be maintained in service during all seasons of the year.

110 I claim:

1. In a car heater, the combination with an outer cylindrical casing communicating at its upper end with the interior of the car and having a closed bottom, of a combustion chamber formed in the lower portion of the casing, having no communication with the interior of said casing, the bottom of said casing having perforations 115 opening into the combustion chamber, a removable grate within the combustion chamber, an inner cylindrical casing arranged within the outer casing, the ends of which inner casing are open, the lower portion of which inner casing surrounds the combustion chamber, a fuel chute leading downward through the inner casing and discharging into the combustion chamber, and a pair of plates arranged to slide on top of the combustion chamber, the forward 120 125 130

ends of which plates enter the chute for controlling the discharge of fuel therethrough.

2. In a car heater of the class described, 5 the combination with an outer cylindrical casing communicating at its upper end with the interior of the car and having a closed bottom, of a combustion chamber formed in the lower portion of said casing and having 10 no communication with the interior of said casing, the bottom of said casing having perforations opening into the combustion chamber, a fuel chute leading downward through the center of the outer casing and 15 discharging into the combustion chamber and a pair of oppositely disposed plates arranged for sliding movement on top of the combustion chamber, the inner ends of which plates are notched and project into the lower 20 end of the fuel chute for controlling the passage of fuel therethrough.

3. In a car heater of the class described, 25 the combination with an outer cylindrical casing communicating at its upper end with the interior of the car and having a closed bottom, of a combustion chamber formed in the lower portion of the casing, having no communication with the interior of said casing, the bottom of said casing having perforations opening into the combustion chamber, a perforated grate supported within the combustion chamber above the bottom of the casing, a fuel chute leading downward through the center of the outer casing and 30 discharging into the perforated grate within the combustion chamber, a pair of oppositely disposed plates arranged for sliding movement on top of the housing, the inner ends of which plate are notched and project 35 into the lower end of the fuel chute for controlling the passage of fuel therethrough, and a cylindrical wall supported within the outer casing so as to form annular spaces between said wall, the outer casing and 40 the fuel chute.

4. In a car heater of the class described, 45 the combination with an outer cylindrical casing communicating at its upper end with the interior of the car and having a closed bottom, of a combustion chamber formed in

the lower portion of the casing, having no communication with the interior of said casing, the bottom of said casing having perforations opening into the combustion chamber, a fuel chute leading downwardly 55 through the center of the outer casing and discharging into the combustion chamber, a pair of independently adjustable oppositely disposed plates arranged for sliding movement on top of the combustion chamber, the inner ends of which plates are notched and project into the lower end of the fuel chute for controlling the passage of fuel therethrough, a cylindrical wall supported within the outer casing so as to form 60 annular spaces between said wall, the outer casing and the fuel chute, and the lower portion of which wall partially incloses the combustion chamber in the bottom of the outer casing. 70

5. In a car heater of the class described, an outer cylindrical casing communicating at its upper end with the interior of the car and having a closed bottom, a combustion chamber formed in the lower portion of the 75 casing, having no communication with the interior of said casing, the bottom of said casing having perforations opening into the combustion chamber, a damper arranged to slide on the bottom of the casing for closing 80 the perforations therein, there being an opening through the wall of the outer casing into the combustion chamber, a door normally closing said opening, a fuel chute leading downwardly through the center of 85 the casing and discharging into the combustion chamber, a perforated grate supported within the combustion chamber above the bottom thereof, and a cylindrical wall supported within the outer casing so as to form 90 annular spaces between said wall, the outer casing and the fuel chute, which annular spaces extend to the top of the heater.

In testimony whereof I hereunto affix my signature in the presence of two witnesses, 95 this 18th day of Sept., 1911.

DAVID R. SAUNDERS.
